US00D547428S

(12) **United States Design Patent** (10) **Patent No.:** **US D547,428 S**
(45) **Date of Patent:** **** Jul. 24, 2007**

(54) **LATTICE GRID**

(75) Inventors: **Ohler L. Kinney, Jr.**, Overland Park, KS (US); **Kathryn L. Pullen**, Lenexa, KS (US); **Eldon F. Mockry**, Lenexa, KS (US)

(73) Assignee: **SPX Cooling Technologies, Inc.**, Overland Park, KS (US)

(**) Term: **14 Years**

(21) Appl. No.: **29/226,669**

(22) Filed: **Apr. 1, 2005**

(51) LOC (8) Cl. **23-01**

(52) U.S. Cl. **D23/351**

(58) **Field of Classification Search** ..... D23/351, D23/354; 261/110, 111, 108, DIG. 11, DIG. 72; 52/578

See application file for complete search history.

(57) **CLAIM**

The ornamental design for a lattice grid, as shown and described.

DESCRIPTION

FIG. 1 is a side view of the lattice grid device, showing our new design; and,

FIG. 2 is perspective view thereof.

The broken line disclosure in the views is understood to be for illustrative purposes only and forms no part of the claimed design.

1 Claim, 2 Drawing Sheets

FIG. 1**FIG. 2**
